APPARATUS FOR THE REGULATION OF
COOLING IN INTERNAL-COMBUSTION
ENGINES

Wifredo Ricart, Barcelona, Spain

Application August 24, 1943, Serial No. 499,855
In Spain September 1, 1942

4 Claims. (Cl. 123—178)

The arrangements already known for the regulation of the temperature in internal combustion motors during the starting or working of the motor, are made up generally by hand controlled shutters or by suitable compensation circuits, or by combinations of both systems.

These arrangements do not completely satisfy modern exigencies for the working of internal combustion engines and especially those for vehicles that in addition to having to be equipped with radiation members, fans and circulating pumps of such a capacity and service that they can ensure a perfect working of the motor, even under unfavorable conditions of use on hot days and tropical climates, must on the other hand at the moment of starting during cold seasons or in cold climates, eliminate the long period of time necessary for raising to a suitable value the temperature of the cooling fluid and of the lubricating means.

The systems hitherto employed, consisting in thermostats by which and under certain conditions of temperature the cooling water passes through a short circuit, do not correspond to modern exigencies, as they represent an excessive loss of fuel since they keep the circulating water pump and the fan running, so that under determined working conditions of the motor, the result is completely unsuitable.

The object of this invention is shown as a non-limitative example, in the attached drawings in which:

Figure 1 shows, in side view and partially in section, the arrangement of the whole of the cooling system in an internal combustion motor.

Figure 2 is a longitudinal section of the controlling arrangement in a schematic form.

This invention facilitates the heating of the motor in the act of starting by means of an arrangement that couples or uncouples the air cooling fan and the centrifugal pump for the circulating water, and which is made up in the following way:

In the drawings, the radiator as shown by 1, the fan by 2, by 3 the centrifugal pump for the circulation of the water or cooling medium, by 4 the piping conducting the cooling means from the engine jacket 5 to the radiator 1, by 6 the piping conducting the cooling means from the radiator 1 to the pump 3 and by 7 there is indicated the piping that conducts the means from the pump 3 to the jacket of the engine 5.

In the jacket of the engine there is mounted a thermostat 8 in such a way that it is surrounded by the cooling means circulating through 55

the jacket of the engine. The stem 9 of this thermostat penetrates into a chamber 10 of the pressure oil circulating system which receives oil under pressure by a suitable piping not shown. To this chamber 10 there is joined a piping 11 that carries the pressure oil to the clutch for coupling or uncoupling the pump 3 and the fan 2 described later on.

10 The stem 9 coupled to the extensible element of the thermostat 8 is provided with grooves 12 in such a way that they close or open the passage of the pressure oil, in order that this may penetrate into the piping 11 and consequently into the above mentioned clutch for coupling or uncoupling the pump 3 and the fan 2.

15 This clutch is constructed as part of the hand starting apparatus 13, in which there is found a chamber 14, into which by means of the piping 11 there penetrates the pressure oil. This oil 20 acts on a piston 15 joined to a plate 16 which in turn acts on a friction disc 17 mounted in such a way that it may slide lengthwise but cannot turn freely on the hollow shaft 18. To this end, the shaft is provided with a keyway 18' and the 25 disc 17 with a key 17' movably disposed therein. On this shaft 18 there is fixed the driving pulley 19 which, through any appropriate transmission, for example by means of a trapezoidal belt 20 and a pulley 21, drives the fan 2 and the pump 3. To the shaft of the engine there is fixed a drum 22 which according to the position of the plate 16 30 drives by means of the friction disc the pulley 19 as will be stated later on.

35 The arrangement object of this invention acts in the following way:

Supposing that a cold motor has to be started, the movable element of the thermostat 8 and consequently the stem 9 are found in such a position that it closes the access of the pressure oil to the piping 11 and to the chamber 14, in such a way that on the piston 15 there is no pressure and consequently the pulley 19 is uncoupled and at rest, as well as the fan 2 and the pump 3.

40 As soon as the cooling means are warmed up 45 in the engine jacket, passing from a determined temperature to which the thermostat 8 has been regulated, the expandable element of this latter, causes the stem 9 to move in a position to open the passage of the pressure oil to the piping 11 and consequently to the chamber 14 in which it acts on the piston 15. Under the action of the oil, the piston is displaced causing the plate 16 50 forming part of the same to follow. This plate pushes the friction disc 17 towards the drum 22 which turns together with the shaft of the motor,

causing the said disc 17 to turn and consequently making the shaft 18 turn, on which is mounted the pulley 19 which drives the fan 2 and the pump 3. With this there takes place the reactivation of the circulation of the cooling means in the jacket of the motor, as well as the supplementary cooling by air.

It will be understood that this invention may be carried out also in a different way from that described and that the component parts may present forms and arrangements differing from those described, without leaving the limits of this invention.

I claim:

1. In a cooling system for an internal combustion engine having a lubricating system and means for circulating lubricant therethrough under pressure, a cooling medium circuit and pump means for circulating cooling medium through said circuit, a cooling fan, means for actuating said fan and pump means and comprising clutch means for interconnecting said actuating means on the one hand and said fan and pump means on the other hand, and means for placing said clutch means under the influence of pressure lubricant from said lubricating system and for removing said clutch means from said influence in accordance with the temperature of the cooling medium in said cooling medium circuit. 20

2. The relationship of parts recited in claim 1, said last-named means being thermostat-controlled, and a controlling thermostat arranged in said cooling medium circuit and extending into 5 said lubricating system.

3. In a cooling system for an internal combustion engine having a pressure fluid system and means for circulating fluid therethrough under pressure, a cooling medium circuit and pump 10 means for circulating cooling medium through said circuit, a cooling fan, means for actuating said fan and pump means and comprising clutch means for interconnecting said actuating means on the one hand and said fan and pump means on 15 the other hand, and means for placing said clutch means under the influence of pressure fluid from said pressure fluid system and for removing said clutch means from said influence in accordance with the temperature of the cooling medium in said cooling medium circuit.

4. The relationship of parts recited in claim 3, said last-named means being thermostat-controlled, and a controlling thermostat arranged in said cooling medium circuit and extending into 25 said pressure fluid system.

WIFREDO RICART.
